UNITED STATES PATENT OFFICE.

IRVIN ROSENFIELD, OF NEW YORK, N. Y.

CHANGE-MAKING MACHINE.

No. 881,443.

Specification of Letters Patent. Patented March 10, 1908.

Application filed October 31, 1907. Serial No. 400,053.

To all whom it may concern:

Be it known that I, IRVIN ROSENFIELD, a citizen of the United States, residing at New York city, Bronx, county and State of New York, have invented new and useful Improvements in Change-Making Machines, of which the following is a specification.

This invention relates to a change-making machine which will deliver, up to a dollar, the correct change between the purchase price and the amount received.

The construction of the machine is simple and its operation reliable, so that mistakes in making change are effectively prevented.

In the accompanying drawings: Figure 1 is a front elevation, partly broken away, of my improved change-making machine; Fig. 2 a vertical section on line 2--2, Fig. 1; Fig. 3 a plan of the coin magazines and levers; Fig. 4 a detail of the coin-releasing slide; Fig. 5 a cross section on line 5--5, Fig. 4; Fig. 6 a detail of one of the coin magazines; Fig. 7 a similar detail showing the parts in a different position; Fig. 8 a section on line 8--8, Fig. 6, with the coins removed; Fig. 9 a rear view of the slotted disk; Fig. 10 a side view thereof, and Fig. 11 a detail showing the engagement of said disk with the coin controlling levers.

The frame 20 of the machine is provided with a suitable number of coin magazines each adapted for the reception of a stack of coins. As shown five magazines 21, 22, 23, 24 and 25 are employed that contain respectively pennies 26, dimes 27, nickels 28, quarters 29 and half-dollars 30. The magazines are open at their bottom and the stacks of coins are normally supported by a series of lugs or coin rests 31, integral with a horizontally movable spring-influenced slide 32. This slide may be advanced by its handle to withdraw supports 31 simultaneously from all the magazines, while upon the release of the handle the slide is returned to its normal position by its spring 33. The reduced sections of the slide between lugs 31 are beveled as shown in Fig. 5, so that the liberated coins may freely glide into the delivery chute 34.

Means are provided for releasing, from the proper magazines, such coins as are required to make the correct change, said means being as follows: A disk 35 rotatable on a pivot 36 is provided at its front with a scale 37 having one hundred divisions, representing the number of cents in a dollar. Disk 35 may be set by a coöperating fixed

dial 38 having a corresponding peripheral scale 39 opposite scale 37. Disk 35 is adapted to actuate, in manner hereinafter described, a series of elbow levers 40, 41, 42, 43 and 44, fulcrumed on a common arbor 45 and provided on their rear arms with plates 46 beneath the several coin magazines 21--25. Plates 46 are slotted as at 47 to straddle projections 31 of slide 32 and thus reach the bottom coins of the several stacks, against which they are held by the lower lever-arms weighted as at 48. Disk 35 is provided on its back with a series of recesses or slots, arranged in concentric zones, the number of such zones corresponding to the number of coin-levers 40--44.

Lever 40, controlling the discharge of coin from the penny magazine 21, is provided with a foot 49 having five steps. These steps 75 extend transversely across the first or outer zone 50 of disk 35, said zone being divided into twenty parts, each containing five steps. If disk 35 is so set that its first step 50^a becomes alined with foot 49 of lever 40, the latter 80 is locked against movement, as its step 49^a will encounter step 50^a. By turning the disk through one division of scale 37 and thereby bringing step 50^b opposite foot 49, the support for step 49^a is withdrawn, so that the lever 85 may be tilted until step 49^b engages step 50^b. This tilting of the lever will, upon the withdrawal of slide 32, be effected by the weight of the coin stack in magazine 21, so that plate 46 together with the stack will be 90 lowered a distance equal to the thickness of a single coin. In this way the bottom coin will be lowered to clear magazine 21 and permit its expulsion therefrom by slide 32. If disk 35 is so turned that step 50^c becomes 95 alined with foot 49, the latter will tilt until checked by step 49^c so that two coins will be released. In like manner a co-action of steps 50^d, 49^d will release three coins, while the co-action of steps 50^e, 49^e will release 100 four coins.

Concentric to outer zone 50, disk 35 is provided with four inner zones 51, 52, 53, 54 adapted to actuate levers 41, 42, 43, 44 respectively. Foot 55 of lever 41 is provided 105 with three steps, while the slots of the corresponding second zone 51 are composed of a narrow section 51^a merging into a wider section 51^b. When the parts are so positioned that slot-section 51^a becomes alined 110 with step 55^a, a single dime will be released from magazine 22, while, when slot-section

51^b becomes alined with step 55^b, two dimes will be released. The slots of the third zone 52 are of uniform width and are adapted to co-act with the foot 56 of lever 42, for the 5 release of a single coin from nickel magazine 23. In like manner the slots of the fourth zone 53, co-acting with foot 57 of lever 43, are adapted to release single quarters from magazine 24, while the slots of the innermost zone 54, co-acting with foot 58 of lever 44, are adapted to release single half-dollars from magazine 25.

As has been stated, zone 50 is divided into 20 sections, each having five steps, thus 15 making one hundred steps in all. The relative arrangement of the slots in disk 35 is such that those slots which are radially alined with any one step, release such coin levers as will deliver one cent more in change 20 than the levers released by the slots alined with the preceding step. Thus, when disk 35 is so turned that step 50^b on line 1, becomes alined with the coin-levers, the penny-lever 40 will tilt for the distance of a single 25 step, while none of the other levers 41—42 will be moved, the disk 35 being imperforate between its steps 50^b and its center. In this way but a single cent will be discharged. If disk 35 is so moved as to carry the succeeding steps 50^c, 50^d or 50^e opposite the coin-levers, two, three or four cents will be respectively discharged. If step 50^a on line 30 2, is brought opposite the coin-levers, the penny-lever 40, as well as the levers 41, 43, 35 44 will encounter solid sections of the disk, the nickel lever 42 only entering its slot 52, so that a five cent piece is discharged. With the position shown in Fig. 11, there will be discharged four pennies, two dimes and one 40 quarter, because a step 50^e, a wide dime slot-section 51^b, and a quarter slot 53, are brought in alinement with the coin-levers, (Fig. 9).

The machine may be so operated that 45 either the mentally calculated change is delivered by it, or that it will itself calculate and deliver the correct change. In the first case, disk 35 is turned until the figure on scale 37 corresponding to the amount of 50 change desired is brought opposite the zero mark of scale 39. In this position the proper slots of disk 35 become alined with their coin-levers, so that these levers will become unlocked. By now advancing slide 32, 55 props 31 are withdrawn from all the coin stacks, so that the latter become supported upon plates 46 only. Thus the coin stacks on the liberated levers will cause the latter to tilt and thereby lower such coins, as will 60 aggregate the change desired, out of the magazines. Slide 32 being next retracted, lugs 31 will sweep the exposed coins off plates 46 and into the delivery chute 34, while the lugs 31 will be again returned be-

neath the coins remaining in the magazines. 65 The tilted coin-levers becoming thus unburdened, will return to their normal position by counterweights 48, ready for the next manipulation. The operation is precisely the same when the machine itself is to calculate the amount of change. In that case the figure on scale 37 corresponding to the value of the coin received is brought opposite that figure on scale 39 which corresponds to the purchase price, so that in this way the subtraction between the coin received and the purchase price is mechanically performed. 70

It will be seen that my machine is of simple construction and that all parts coöperate in such a manner that the exact change required is released, so that reliance may be placed on its correctness. 80

I claim:

1. In a device of the character described, a rotatable disk, a series of coin-levers adapted to operatively engage the same, first coin supporting means connected to the levers, and a slide provided with second coin supporting means, substantially as specified. 85

2. In a device of the character described, a rotatable disk having a series of concentrically arranged recesses, a series of coin levers having stepped feet adapted to engage said recesses, and coin-controlled means for tilting said levers, substantially as specified. 90

3. In a device of the character described, a series of coin magazines, levers having first coin supporting means below said magazines, a disk having a series of recesses adapted to be engaged by said levers, and a slide 100 having second coin supporting means, substantially as specified.

4. In a device of the character described, a series of coin magazines, levers having first coin supporting means below said magazines, stepped feet on the levers, a disk having a series of recesses adapted to be engaged by said feet, and a slide having second coin supporting means, substantially as specified. 105

5. In a device of the character described, 110 a series of coin magazines, levers having slotted plates beneath said magazines, means for locking and unlocking said levers, and a slide having projections that engage the slotted plates, substantially as specified. 115

6. In a device of the character described, a series of coin magazines, levers having slotted plates beneath said magazines, stepped feet on said levers, a disk having a series of concentric recesses adapted to be engaged 120 by said feet, and a slide having projections that engage the slotted plates, substantially as specified.

7. In a device of the character described, a rotatable disk having a stepped zone, and a series of recessed zones, combined with a series of coin-levers adapted to engage said zones, and with coin-releasing means con-

trolled by the levers, substantially as specified.

8. In a device of the character described, a rotatable disk having a stepped zone, a series of recessed zones, combined with a series of coin levers having feet adapted to engage said zones, first coin supports on the levers, a slide having second coin supports, and coin

magazines above the first coin supports, substantially as specified.

Signed by me at New York city, (Manhattan,) N. Y., this 30th day of October, 1907.

IRVIN ROSENFELD.
